Primary Examiner—Dominic Simone*Attorney, Agent, or Firm*—Edward B. Anderson[57] **CLAIM**

The ornamental design for a fixed-position antenna-mounting bracket assembly, as shown.

DESCRIPTION

FIG. 1 is a front perspective view of a fixed-position antenna-mounting bracket assembly showing our design;

FIG. 2 is a top plan view of the fixed-position antenna-mounting bracket assembly of FIG. 1;

FIG. 3 is a bottom plan view of the fixed-position antenna-mounting bracket assembly of FIG. 1;

FIG. 4 is a front view in elevation of the fixed-position antenna-mounting bracket assembly of FIG. 1;

FIG. 5 is a rear view in elevation of the fixed-position antenna-mounting bracket assembly of FIG. 1;

FIG. 6 is a side view of the fixed-position antenna-mounting bracket assembly of FIG. 1 as seen from the left-hand side of FIG. 4; and,

FIG. 7 is a side view of the fixed-position antenna-mounting bracket assembly of FIG. 1 as seen from the right-hand side of FIG. 4.

The broken lines in FIG. 1 showing a fragment of an antenna are for illustrative purposes only and form no part of the claimed design.
